UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,139,980.

Specification of Letters Patent.

Patented May 18, 1915.

Application filed February 5, 1915. Serial No. 6,210.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention has reference more particularly to linotype machines of the general organization represented in U. S. Letters Patent to O. Mergenthaler, No. 436532, wherein circulating matrices are selected 15 and assembled in line together with expanding spaces, and the line thereafter presented to the front of a slotted mold, expanded or justified between a pair of confining jaws, and finally, after the casting 20 operation, elevated from the jaws and distributed.

In practice it is necessary to change frequently the length of the slugs or linotypes produced, according to the width or measure 25 of the page or column to be printed. Consequently, the mold slot in which the slugs are cast is made variable in length, and the confining jaws are also made adjustable to correspond, so that lines of one length or another may be used at will.

It is the principal aim of my present invention to enable the operator seated at the keyboard to adjust the movable jaw instantly and accurately to any required measure; and to this end, it consists in means 35 within reach of the operator for locking and unlocking the jaw and for moving it to definite positions.

In the accompanying drawings, I have 40 shown my invention as applied merely by way of example and in preferred form, and obviously many changes and variations may be made therein, which will still be comprised within its spirit. I therefore desire 45 it to be understood that I do not limit myself to any specific form or embodiment, except in so far as such limitations are specified in the claims.

Referring to the drawings: Figure 1 is a 50 rear perspective view of a portion of a linotype machine, having my invention applied thereto; Fig. 2 is an end view thereof, partly in section and broken away; Fig. 3 is a top plan view of a portion of the vise frame; Fig. 4 is a vertical section, taken through 55 the vise frame, partly broken away; and

Fig. 5 is a somewhat similar view, showing the parts in different position.

I have limited the accompanying drawings to those parts of a commercial Mergenthaler linotype machine which are necessary to an understanding of my invention. As to all other parts, the machine may be of any ordinary or improved construction.

The composed line of matrices and spacers 60 is presented to the mold by the first elevator B (shown only in part), which is arranged to slide vertically in the portion of the machine commonly known as the "vise frame," and herein designated by the letter A. Supported in the vise frame are the jaws C and D adapted to engage the opposite ends of the composed line and clamp it tightly therebetween. The left-hand jaw D is mounted, as usual, to slide horizontally in a guideway 65 in the vise frame, so that the distance between it and the opposing jaw C may be varied according to the length of line employed. The position of the jaw D is determined by the adjustable rod E, which 70 may be connected directly therewith, or merely abut against it, as shown. The rod E is slidably supported in the frame and passes through the nut or block F, which is arranged between a fixed part of the frame 75 and the vertically movable wedge J, the rod E being connected to the nut by the locking bolt or latch G mounted thereon and which 80 is formed with teeth G² to engage the circumferential teeth or serrations E¹ of the 85 rod.

The parts so far described are or may be 90 substantially the same as those shown in U. S. Letters Patent No. 816841, to R. M. Bedell. It may be pointed out, however, 95 that the nut F serves as a rigid support for the rod E and the connected jaw D, and as a means for moving the rod endwise to effect the well-known clamping action of the jaw, this action being controlled by the vertically 100 movable wedge J in the customary way.

In order to effect the adjustment of the jaw D, it is merely necessary to disconnect the locking bolt G from the rod E and move the latter endwise in one direction or the other, as required. Hence, the rod is provided at its outer end with an arm E², to which is connected a bar or member E³ extending toward the right across the top of 105 the vise frame A and terminating within reach of the operator seated at the keyboard,

it being provided at its end with an up-standing finger E^4 to facilitate its operation, and with a pointed E^6 coöperating with a stationary scale A^1 on the frame to enable the operator to determine accurately 5 the extent of adjustment.

Referring now to the locking means for holding the rod E in its adjusted position, it will be noted that the bolt G is formed with 10 a central elongated slot G^1 through which the rod passes, and that it is formed with teeth G^2 at the upper end of the slot to engage the teeth E^1 of the rod. This construction is advantageous in that it prevents any 15 twisting or binding of the parts, such as has heretofore been possible. The bolt G is operated by a lever H pivoted at one end, as at H^1 , to the vise frame A , and engaging at its other end in a hole or aperture G^3 20 in the upper end of the bolt. A spring H^2 tends normally to depress the bolt G and hold it with its teeth G^2 in engagement with the teeth E^1 of the rod and thus lock the latter in its adjusted position.

25 In order to unlock the rod E against the action of the spring H^2 , there is provided a longitudinally movable bar or member, I , underlying the lever H and seated upon and carried by the bar E^3 , it being formed at its 30 end with an upstanding finger I^2 located in immediate proximity to the finger E^4 of the bar E^3 . Referring to Figs. 2, 4 and 5, it will be seen that the bar E^3 is provided with a series of buttons or protuberances E^5 , which 35 normally engage in recesses or depressions I^1 formed in the underside of the bar I , (Fig. 5). Now, when the bar I is shifted longitudinally, its recesses I^1 will be disengaged from the buttons E^5 , producing in 40 effect a cam-action which causes the bar to be moved laterally, away from the underlying bar E^3 . This lateral movement of the bar I effects the rocking of the lever H , which thereupon elevates the bolt G against 45 the action of the spring H^2 and disengages its teeth G^2 from the teeth E^1 of the rod E . A spring I^3 , connected at one end to the bar E^3 and at its opposite end to the bar I , serves 50 to shift the latter back to its original position and restore the engagement of the recesses I^1 with the buttons E^5 . The operation of the parts will now be clear. When the position of the jaw D is to be altered, the operator grasps the fingers I^2 and E^4 55 and presses the former toward the latter, thus shifting the bar I longitudinally relatively to the bar E^3 and effecting the unlocking of the rod E in the manner just described which condition of the parts is 60 shown by full lines in Fig. 4. The operator then moves the two bars as a whole to the required extent, (as shown, for example, by dotted lines in Fig. 4), being guided in this action by the scale A^1 . He next releases 65 the fingers I^2 and E^4 , permitting the spring

I^3 to return the bar I to its original position with relation to the bar E^3 , and permitting the spring H^2 to depress the bolt G and lock the bar E in its new position.

It will thus be seen that by this arrangement of the parts, the operator is enabled to adjust the jaw to any required position and in the least possible time, the operating members for both the adjusting means and the locking means being so located as to be manipulated easily and simultaneously. As previously stated, I have shown my invention only in preferred form and by way of example, and as applied to a specific style of machine, but obviously many modifications and alterations therein, and in its mode of adaptation, will suggest themselves to those skilled in the art without departure from its scope.

Having thus described my invention, what I claim and desire to secure by Letters Patent of the United States is as follows:

1. In a typographical machine, the combination of a line confining jaw, a sustaining nut therefor, an adjustable toothed rod located between said parts, and a locking bolt mounted in the nut and having a central elongated slot through which the rod passes and formed with teeth at the upper end of the slot to engage the teeth of the rod. 90

2. In a typographical machine, the combination of a line confining jaw, a sustaining nut therefor, an adjustable toothed rod located between said parts, and a locking bolt mounted in the nut and having a slot 100 through which the rod passes, said bolt being formed with teeth to coöperate with those on the rod.

3. In a typographical machine, the combination of an adjustable line confining jaw, 105 a latch to hold the jaw in its adjusted position, a longitudinally movable bar for adjusting the jaw, a second bar seated upon the first and movable longitudinally and relatively thereto, means whereby the longitudinal relative movement of the second bar also effects its lateral or sidewise movement, and devices actuated by the sidewise movement of the second bar for moving the latch. 110

4. In a typographical machine, the combination of the vise-frame, a line confining jaw slidably arranged therein, a sustaining nut therefor, an adjustable rod located between the jaw and nut, a locking bolt mounted in the nut and movable so as to be engaged with and disengaged from the rod, and means for effecting the movement of said bolt, said means including a longitudinally movable bar extending toward the right across the vise-frame and located with in the reach of the operator seated at the keyboard, and devices connected to the locking bolt and actuated by the longitudinal movement of the bar. 120

5. In a typographical machine, the com- 125

- bination of a line confining jaw, a sustaining nut therefor, an adjustable rod located between said parts, a locking bolt mounted in the nut and movable so as to be engaged with and disengaged from the rod, a longitudinally movable bar, means whereby the longitudinal movement of said bar will also effect its lateral or sidewise movement, and devices actuated by the lateral movement of the bar for moving the locking bolt. 5
6. In a typographical machine, the combination of a line confining jaw, a sustaining nut therefor, an adjustable rod located between said parts, a locking bolt mounted in the nut and movable so as to be engaged with and disengaged from the rod, a longitudinally movable bar, means whereby the longitudinal movement of said bar will also effect its lateral or sidewise movement, a pivoted lever actuated by the lateral movement of the bar for disengaging the locking bolt from the adjustable rod, and a spring for effecting the reengagement of the bolt with the rod. 15
7. In a typographical machine, the combination of a line confining jaw, a sustaining nut therefor, an adjustable rod located between said parts, a locking bolt mounted in the nut to engage and hold the rod in its adjusted position, a device for disengaging the bolt from the rod, a bar movable longitudinally to actuate said device, and a spring for returning the bar to its normal position. 20
8. In a typographical machine, the combination of a line confining jaw, a sustaining nut therefor, an adjustable rod located between said parts, a locking bolt mounted in the nut to engage and hold the rod in its adjusted position, a pivoted lever for disengaging the bolt from the rod, a bar movable longitudinally and laterally for actuating the lever, a spring to return the bar to its original position, and a second spring to effect the reengagement of the bolt with the rod, upon the return of the bar, substantially as shown and described. 25
9. In a typographical machine, the combination of the vise-frame, a line confining jaw slidably arranged therein, means for adjusting the jaw to different positions, a latch to hold the jaw in its adjusted position, and means for operating said latch, the said means including a longitudinally movable bar extending toward the right across the vise-frame within reach of the operator seated at the keyboard, and devices connected to the latch and actuated by the longitudinal movement of the bar. 30
10. In a typographical machine, the combination of the vise-frame, a line confining jaw adjustably mounted therein, a latch to hold the jaw in its adjusted position, a longitudinally movable bar extending toward the right across the vise-frame within reach of the operator, and means whereby the longitudinal movement of said bar effects the actuation of the latch. 35
11. In a typographical machine, the combination of a line confining jaw, means for adjusting it to different operative positions, a latch to hold it in its adjusted position, and means for actuating the latch, the two said means including separate and distinct operating members movable relatively to each other to disengage the latch and movable conjointly to adjust the line confining jaw. 40
12. In a typographical machine, the combination of an adjustable line confining jaw, a latch to hold the jaw in its adjusted position, means for effecting the adjustment of the jaw, including a manually operable member, and a second member carried by and movable with the first for actuating the latch. 45
13. In a typographical machine, the combination of the vise-frame, a line confining jaw adjustably arranged therein, a latch to hold the jaw in its adjusted position, means for effecting the adjustment of the jaw, including a longitudinally movable bar extended across the frame within reach of the operator, and a second bar carried by and movable with the first, the said second bar being movable longitudinally and relatively to the first in any of the latter's different positions for actuating the latch. 50
14. In a typographical machine, the combination of the line confining jaw D, means for adjusting the jaw, the locking bolt G, and means for actuating the bolt, the said adjusting means including the longitudinally movable bar E³ formed with the protuberances E⁵, and the actuating means including the longitudinally movable bar I carried by the bar E³ and formed with the recess I¹ wherein the protuberances E⁵ engage, all for the purpose described. 55
15. In a typographical machine, the combination of the adjustable line confining jaw D, the longitudinally movable bar E³ for effecting its adjustment, the locking bolt G for holding the jaw in its adjusted position, the bar I seated upon and carried by the bar E³, and movable relatively thereto to effect the actuation of the locking bolt, and the spring I³ connected to the bars E³ and I respectively and tending to hold the latter in its normal position on the former. 60
- In testimony whereof, I have affixed my signature in presence of two witnesses. 110
